UNITED STATES PATENT OFFICE.

SAMUEL B. WILLIAMS, JR., OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed August 17, 1920. Serial No. 404,079.

To all whom it may concern:

Be it known that I, SAMUEL B. WILLIAMS, Jr., a citizen of the United States, residing at Brooklyn, in the county of 5 Kings and State of New York, have invented certain new and useful Improvements in Telephone-Exchange Systems, of which the following is a full, clear, concise, and exact description.

10 This invention relates to telephone systems and particularly to party line working in machine switching systems.

The object of the invention is to provide an improved device of the character 15 set forth in the patent to Hoyland, No. 1,158,221 of October 26, 1915. In accordance with this object, an all relay circuit arrangement for accomplishing the desired results has been devised having certain 20 novel features which will clearly appear as the description proceeds.

In the drawings, Fig. 1 diagrammatically represents two party lines with means whereby they may set up connections for 25 reverte calls. On the right of Fig. 1, is shown a circuit for two-party reverte calling and in Fig. 2 is shown a circuit for four-party reverte calling.

The arrangement of a reverte call on a 30 two-party line will first be described. Such a two-party line is shown in the lower left-hand corner of Fig. 1, with the stations 105 and 106 bridged across the line wires T and R, representing the tip and ring sides of the 35 line as they are spoken of by telephone men. The stations 105 and 106, as they are connected to the line wires, are reversed with respect to each other so that ringing current traveling over the tip side of the line will 40 find an open circuit at station 106, but will travel through the condenser and bell of station 105 to ground. On the other hand, ringing current traveling over the ring side of the line will find an open circuit at station 45 105 but will flow through the condenser and bell of station 106.

Let it be assumed that the subscriber at station 105 desires to call the subscriber at station 106. He will, therefore, upon removing 50 his receiver from its switch hook cause the line switch, diagrammatically represented by the brushes 114, to connect to the

selector switch 125. In order to make a reverte call, the subscriber at station 105 must dial a special number. We will, in 55 this case, assume that the special number is 5. Upon manipulating his dial switch to send a train of five impulses, the brushes of selector switch 125 will be set on their fifth contacts, 107 to 109 inclusive. A circuit is thereupon established from ground, battery, left-hand winding of relay 115, back contact and outer left-hand armature of relay 117, terminal 108, conductor R, through the substation at 105, conductor T, 60 terminal 107, inner left-hand armature and back contact of relay 117, and the right-hand winding of relay 115 to ground. Relay 115 is energized and establishes a circuit from ground, the armature and front 70 contact of relay 115, the winding of relay 116 to battery and ground. Relay 116 attracts its armatures and at its left-hand armature, places a holding ground on the terminal 109 of the calling line. 75

When the subscriber at station 105 has set up this connection, he replaces his receiver on its hook, whereupon the relay 115 becomes deenergized. Relay 116, however, is slow to release and therefore a circuit is 80 established from ground, the armature and back contact of relay 115, right-hand armature and front contact of relay 116, armature and back contact of relay 124, the normal contacts of the right-hand armature of 85 relay 123, and the winding of relay 117 to battery and ground. Relay 117 attracts its armatures and establishes a holding ground for relay 116 extending from ground, the inner right-hand armature and 90 front contact of relay 117, and the winding of relay 116 to battery and ground. At the same time, relay 117 establishes a circuit for the energization of relay 118 so that the interrupter 121 is connected to the right-hand armature of relay 119. 95

Special attention should be attached to the connection of relays 119 and 120. Upon the first closure of the circuit through interrupter 121, ground is placed on the right-hand armature of relay 119 through its back contact, the winding of relay 120 and the right-hand winding of relay 119 to battery and ground. Relay 120 is energized in this 100

circuit, but the right-hand winding of relay 119 being marginal, relay 119 does not become energized at this time. Relay 120 in attracting its armature extends ground from the left-hand armature of relay 118, the front contact and armature of relay 120, and the left-hand winding of relay 119, but this winding is short circuited at this time due to the ground at the back contact and right-hand armature of relay 119 furnished through the interrupter 121. When the interrupter 121 opens the circuit, relay 119 becomes energized through a circuit including its left-hand winding, the winding of relay 120, and the right-hand winding of relay 119 in series. When the interrupter 121 again closes the circuit to ground, the winding of relay 120 will be short circuited due to the ground furnished at the right-hand armature and front contact of relay 119, and the ground furnished through the armature of relay 120. Thus, relay 120 becomes deenergized and relay 119 is held energized through its right-hand winding. As the interrupter 121 again opens the circuit, relay 119 becomes deenergized. Thus, for two complete cycles of operation of the interrupter 121 there is a single complete cycle of operation of relays 119 and 120.

Upon the energization of relay 117, a circuit is closed from a source of ringing current 126 through the back contact and outer left-hand armature of relay 122, the winding of relay 124, the front contact and outer left-hand armature of relay 117, the ring side of the line, the condenser and bell of station 106 to ground, whereby the bell at station 106 is caused to ring. The bell at station 105, at this time, is short circuited due to the ground at the back contact and inner left-hand armature of relay 122 being connected through the front contact and inner left-hand armature of relay 117 to the tip side of the line. Upon the first energization of relay 119, ground is extended from the left-hand armature and front contact of relay 118, the left-hand armature and front contact of relay 119 to the winding of relay 122. The armature of relay 122 now reverses the ringing current, connecting the source of ringing current to the tip side of the line and ground to the ring side, whereby the bell at station 106 ceases to ring and the bell at station 105 begins to ring. As the interrupter 121 functions, relays 119 and 120 will continue to operate, whereby relay 122 is intermittently energized and deenergized and the bells at stations 105 and 106 are alternately rung. When the party at station 106 removes his receiver from its switch hook, the current flowing through relay 124 is increased sufficiently to cause this relay to become energized. Thereupon the circuit for relay 117 is opened and relay 123 becomes energized in series with relay 117 through

the right-hand winding of relay 123. After relay 123 has attracted its armatures and opened the circuit of relay 117, it remains energized through its left-hand winding. As relay 117 becomes deenergized, ringing current is cut off from both bells on the party line, and the subscriber at station 105 noticing that this bell no longer rings, removes his receiver from its hook in order to communicate with the subscriber at station 106. Talking current is furnished through the windings of relay 115 which now becomes energized and furnishes ground to hold relay 116 in place of the ground furnished by relay 117.

It should be noted that if both subscribers replace their receivers, this circuit will not again be set in operation to ring the two bells since relay 123 has locked up to the ground on terminal 109. When both subscribers do replace their receivers, relay 115 becomes deenergized and after an interval, relay 116 retracts its armatures and removes the ground from terminal 109 whereupon the selector switch 125 and the line switch 114 are returned to their normal position in any well-known manner.

In the upper left-hand portion of Fig. 1, there is shown a four-party line; the substation arrangement here is somewhat different from that on a two-party line since a relay is required. Two of the stations, 101 and 104, are reversed with respect to the other two stations, 102 and 103. Stations 101 and 104 differ, in that in one the bell is biased to respond to plus pulsating current only, and in the other, that is station 104, the bell is biased to respond to minus pulsating current only. The same difference applies to stations 102 and 103.

Let it be assumed that the subscriber at station 101 desires to call the subscriber at station 103. In the manner hereinbefore described, the subscriber at station 101 will be required to dial the special number which we will assume to be, in the present instance, 46. As he transmits the first series of four impulses, the selector switch 125 will be set on the terminals 110 to 112 inclusive, whereupon a relay, 215, will be energized in the same manner as relay 115 was energized. Relay 215 in attracting its armature causes the energization of relay 216 which places a ground on conductor 209 connected to terminal 112, to mark this particular circuit as busy and to hold the selector switch 125 and the line switch 113 from releasing. The subscriber at station 101 now dials the second digit of the special number and sends a train of six impulses. Upon the first retraction of its armature by relay 215, a circuit is closed from ground, the armature and back contact of relay 215, the front contact and right-hand armature of relay 216, the left-hand armature and back contact of re-

lay 207, and the winding of relay 208 to battery and ground. Relay 208 closes a circuit for relay 210. A circuit may now be traced from ground, the left-hand armature and front contact of relay 216, the left-hand armature and front contact of relay 210, the normal contacts and left-hand armatures of relays 206, 205, 204, 203, 202 and 201, front contact and right-hand armature of relay 210, and the winding of relay 201 to battery and ground. Relay 201 becomes energized in this circuit and, at the same time, a circuit is established from ground, the right-hand armature and front contact of relay 208, the left-hand armature and back contact of relay 219, the winding of relay 220, and the left-hand winding of relay 219 to battery and ground. Relays 219 and 220 act in exactly the same manner as do relays 119 and 120. Therefore, upon the first closure of the right-hand armature and contact of relay 208, relay 220 energizes. When this armature is retracted, relay 219 becomes energized. When this armature is again attracted, relay 220 becomes deenergized, and when this armature is retracted for the second time, relay 219 becomes deenergized.

Relay 201 upon energizing prepares a circuit for relay 202 from battery and ground, the winding of relay 202, the inner right-hand armature and front contact of relay 201, the back contact of the left-hand armature of relay 220, but since relay 220 is energized at this time, the circuit for relay 202 is incomplete. Upon the end of the first impulse, that is, when relay 215 becomes energized, relay 208 will become deenergized, but relay 210 being slow to release will not retract its armatures unless relay 208 remains deenergized. Upon the retraction of its armatures by relay 208, relay 219 becomes energized. Upon the second retraction of the armatures of relay 215, relay 208 again becomes energized and causes the deenergization of relay 220 whereupon the circuit for relay 202 is now completed through the back contact and left-hand armature of relay 220, the back contact and outer right-hand armature of relay 207, and the front contact and left-hand armature of relay 216 to ground. As relay 202 becomes energized, the circuit for relay 201 is opened at the contacts of the left-hand armature of relay 202. When relay 208 again becomes deenergized, relay 219 becomes deenergized, and when relay 208 becomes energized for the third time, a circuit is established for relay 203 extending from battery, the winding of relay 203, the inner right-hand armature and front contact of relay 202, the front contact and left-hand armature of relay 220, back contact and outer right-hand armature of relay 207 to ground at the front contact and

armature of relay 216. In a similar manner each of the relays 204 to 206, will become energized corresponding to the number of impulses sent so that with a train of six impulses, relay 206 will finally become energized. At the end of this series of impulses, relay 206 will remain energized through its winding, the alternate contacts of its left-hand armature, the front contact and left-hand armature of relay 210, the front contact and left-hand armature of relay 216 to ground. Relay 215 becomes steadily energized and relay 208 retracts its armatures followed after an interval by relay 210. Upon the retraction of its armatures by relay 208, relay 219 becomes energized. When relay 210 retracts its armature, relay 207, which is bridged across the left-hand armature and contact of relay 219 becomes energized. The circuit is now in a stable condition awaiting further action by the subscriber at station 101. This action consists in hanging up his receiver according to instructions and relay 217 will thereupon become energized in the manner in which relay 117 became energized. That is, a circuit is established from ground, the armature and back contact of relay 215, the front contact and right-hand armature of relay 216, the left-hand armature and front contact of relay 207, the left-hand armature and back contact of relay 224, the normal contacts of the right-hand armature of relay 223, and the winding of relay 217 to battery and ground. Relay 217 maintains relay 216 in an energized position and, at the same time, causes the energization of relay 218. A source of plus pulsating current 226 is connected through an interrupter 221, the front contact and outer right-hand armature of relay 218, the condenser 228, and the winding of relay 225 to battery and ground. Relay 225 responds to this character of current and attracts its armature whereby a ground is placed on the inner right-hand armature of relay 218 intermittently in the same manner. Thus relays 219 and 220 are caused to go through their cycle of operations in a similar manner to relays 119 and 120. Upon each turn of relay 219, a ground is extended from the outer right-hand armature and front contact of relay 217, the left-hand armature and front contact of relay 218, the right-hand armature and front contact of relay 219, to the four relays marked 222, 232, 242 and 252 in parallel whereby these relays are simultaneously energized. It will be noted that due to the arrangement of the relays 219 and 220, relay 222, as an example, is energized once for every other closure of the circuit by the interrupter 221.

It will now be noted that when relay 222 is deenergized, ground is extended through the back contact and left-hand armature of

relay 222, the front contact and right-hand armature of relay 206, and thence through the back contacts and outer right-hand armatures of relays 205 to 201 inclusive, the 5 winding of relay 224, the back contact and outer left-hand armature of relay 217, terminal 111, ring side of the line to short circuit the bells at stations 102 and 103. At the same time, plus pulsating current from 10 the source 226 is connected through the back contact and right-hand armature of relay 222, the front contact and left-hand armature of relay 206 and thence through the normal contacts and left-hand armatures of 15 relays 205 to 201 inclusive, the front contact and inner left-hand armature of relay 217, terminal 110, tip side of the line and thence through the bells of stations 101 and 104 in parallel. It will be noted, however, 20 that station 104 will respond only to minus pulsating current, therefore, the bell at station 101 is the only one which will ring during this interval.

As the interrupter 221 functions, and 25 when relay 219 responds, relay 222 will attract its armatures, whereupon the ringing current connections will be changed so that minus pulsating current will now be connected to the ring side of the line in place of ground, and ground will be connected to the tip side of the line in place of plus pulsating current. Minus pulsating current on the ring side of the line causes the bell at station 103 to ring. Thus, the bells at 30 stations 101 and 103 will alternately ring as the relay 222 energizes and deenergizes. When the called subscriber at station 103 responds by removing his receiver from its switch hook, relay 224 will be energized to 35 attract its armatures whereupon relay 223 will become energized through its right-hand winding and, after it attracts its armatures, will remain energized through its left-hand winding. The circuit of relay 217 40 will be opened and relay 217 will retract its armatures bringing the relay 215 into circuit with the subscriber's line to supply talking battery. The circuit of relay 218 is opened at the outer right hand armature 45 and contact of relay 217, whereupon relay 218 becomes deenergized, leaving relays 219, 220 and 206 in their energized conditions 50 they being held through the ground at the left hand armature and front contact of relay 216. At the end of the conversation, when both subscribers hang up their receivers on their switch hooks, relay 215 will become deenergized, followed shortly thereafter by the deenergization of relay 216. 55 The ground will thereupon be removed from the conductor 209 and the selector switch 125 and the non-numerical switch 113 will be returned to normal.

For a complete understanding of the 60 functioning of the four-party revertive set

shown in Fig. 2, the following table is appended. In the first column are given the number of impulses which are sent by the calling subscriber, in the second column are given the relays of the series 201 to 206 inclusive which are energized through the receipt of these impulses, the third column is divided into two sub-columns and each of these is further divided into two columns. In the first sub-column is shown the combination of ringing current for ringing the first station, the letter G standing for ground, the character - standing for minus, and the character + standing for plus pulsating current. In the column 75 headed 1st station, is shown the combination of connections when the relays 222, 232, 242 and 252 are deenergized and under the second column headed 2nd station, is shown the combination of connections when 80 these relays are energized. The last column is subdivided into two columns headed respectively 1st station and 2nd station and shows the number of the stations which are 85 alternately rung.

Impulses.	Relay energized.	Ringing currents.				Stations rung.	
		1st sta.		2nd sta.		1st sta.	2nd sta.
		tip	ring.	tip.	ring.		
1-----	201	G	-	G	+	103	102
2-----	202	G	+	-	G	102	104
3-----	203	-	G	+	G	104	101
4-----	204	G	-	-	G	104	103
5-----	205	G	+	+	G	102	101
6-----	206	+	G	G	-	101	103

What is claimed is:

In a telephone system, a party line, a 105 plurality of substations connected thereto, an impulse transmitter for each said substation, means comprising automatic switches responsive to impulses transmitted by said substation impulse transmitters for extending said line, a ring-back device accessible to said switches, said ring-back device comprising signaling means, relays responsive to impulses transmitted by said substation transmitters for selectively controlling said signaling means to signal the calling and the called parties on said party line, an interrupter comprising a pair of relays successively energized in all possible combinations for alternately connecting said signaling means during one period to signal the called party and during another period to signal the calling party, a relay responsive to a line condition created by the act of the calling party 110 in replacing his receiver on its hook for 115 causing said interrupter to operate, a relay responsive to a line condition created by the act of the called or the calling party in 120 subsequently removing his receiver from its 125 line, and a selector switch responsive to the 130

hook for cutting off said signaling means, a relay responsive to said last-named relay for thereupon locking said interrupter out of service until said ring-back device is released, and releasing means responsive to a line condition created by the act of both the calling and called parties in replacing

their receivers on their hooks for restoring said ring-back device to normal and for releasing said automatic switches. 10

In witness whereof, I hereunto subscribe my name this 11th day of August A. D., 1920.

SAMUEL B. WILLIAMS, JR.
